DESIGN FOR A BOTTLE

Charles A. Neumann, Bardstown, Ky., assignor
to Bardstown Distillery, Inc., Bardstown, Ky., a corporation of Delaware

Application May 25, 1936, Serial No. 62,820

Term of patent 7 years

To all whom it may concern:

Be it known that I, Charles A. Neumann, a citizen of the United States, and a resident of Bardstown, Nelson County, and State of Kentucky, have invented a new, original, and ornamental Design for a Bottle, of which the following is a specification; reference being had to the accompanying drawing, forming part thereof.

Fig. 1 is a front view of a bottle showing my new design; and

Fig. 2 is an edge view thereof.

I claim:

The ornamental design for a bottle as shown
and described.

CHARLES A. NEUMANN.
